JET AIRPLANE OR THE LIKE

Mike Tecton, 5101 45th St. NW, Washington, D.C.

Filed Oct. 24, 1965, Ser. No. 87,910

Term of patent 14 years

(Cl. D71—1)

FIG. 1 is a top perspective view of a jet airplane or the like, embodying my new design;
FIG. 2 is a bottom view thereof;
FIG. 3 is a side elevational view thereof;
FIG. 4 is a top plan view thereof; and,
FIG. 5 is a rear elevational view thereof.

I claim:

The ornamental design for a jet airplane or the like, substantially as shown.
